[57] **CLAIM**

The ornamental design for a power driven lawn trimmer, as shown.

DESCRIPTION

FIG. 1 is a perspective view of the lawn trimmer showing my new design;

FIG. 2 is a top plan view of the said lawn trimmer;

FIG. 3 is a side elevation of said lawn trimmer;

FIG. 4 is an end elevation of the engine shown in FIGS. 1-3; and

FIG. 5 is an end elevation of the cutter head, taken on the line 5—5 of FIG. 3.
